UNITED STATES PATENT OFFICE.

SILAS H. RAYMOND, OF GRAND RAPIDS, MICHIGAN, ASSIGNOR TO GEORGE E. RAYMOND & CO., OF SAME PLACE.

VEHICLE-SPRING.

SPECIFICATION forming part of Letters Patent No. 399,210, dated March 5, 1889.

Application filed November 10, 1888. Serial No. 290,487. (No model.)

To all whom it may concern:

Be it known that I, SILAS H. RAYMOND, a citizen of the United States, residing at Grand Rapids, county of Kent, State of Michigan, have invented a new and useful Vehicle-Spring, of which the following is a specification.

This invention has for its object the peculiar construction and association of levers and springs with the body and side bars of a vehicle, as below described and claimed.

In the drawings forming a part of this specification, Figure 1 is an under plan view, Fig. 2 a section on line 2 2 in Fig. 1, and Fig. 15 3 is an enlarged view, of one of the springs.

Referring to the lettered parts of the drawings, B is a frame, which will serve to illustrate the bottom of a vehicle-body. (Shown in Fig. 1 bottom side up.) A are the ordinary side bars. (Here shown broken.) Two levers, D, are pivoted to each end of the body at e. From this point the levers extend laterally in both directions, their inner endslapping a short distance, Figs. 1 and 2, and their outer ends being attached to some suitable support—as, for instance, as here shown, to the side bars, A, which are parallel with the sides of the body. The lapped ends of the levers D rest upon springs—that is, they are supported by springs—and when the vehicle-body is borne downward the lapped ends of said levers yield downward against a spring-resistance.

In Fig. 3 is shown a convenient spring for this purpose, consisting of a hair-pin lever portion, f, spirals a, and ends S S, for attaching the springs to the body-frame, so as to bring the portion f against the under side of the lapped ends of the levers D, as in Figs. 1 and 2. Two of these springs are here shown at each end of the body, but one will serve, as the lever portion f will support both of the lapped ends of the levers D if the single spring is made of proper strength and stiff-

ness for the purpose. While a double spring with its lever part connecting the two and having the friction-roller is not new, *per se*, yet in the novel combination of parts, with levers having the non-slotted ends, I effect advantageous results in strength, convenience in construction, and place of location, and a more accurate balance of the body when the burden therein is unequally distributed. A vehicle-body thus supported by spring-actuated levers will move up and down on a level, it matters not at what place the burden is located. Thus a heavy person sitting at one corner will not bear that corner of the body down more than the entire portion of the body.

Having thus described my invention, what I claim as new, and desire to secure by Letters Patent of the United States, is—

1. In a vehicle, the levers pivoted to the body and having the non-slotted lapping ends resting upon a spring attached to the body, the other ends of said levers being attached to supports disconnected from the body, substantially as set forth.

2. In combination, a vehicle-body, the levers having the non-slotted lapping ends, and spiral springs having the connecting hair-pin arm contacting the under side of said lapping ends, substantially as set forth.

3. The combination of a vehicle-body, the levers at each end pivoted thereto and having the lapping ends, the spiral springs having the hair-pin lever portions supporting said lapped ends of the levers, and the side bars to which the outer ends of the levers are attached, substantially as set forth.

In testimony of the foregoing I have hereunto subscribed my name in presence of two witnesses.

SILAS H. RAYMOND.
